UNITED STATES PATENT OFFICE

LOUIS COHEN, OF WASHINGTON, DISTRICT OF COLUMBIA

RADIO SIGNALING

Application filed August 30, 1928. Serial No. 303,087.

(GRANTED UNDER THE ACT OF MARCH 3, 1883, AS AMENDED APRIL 30, 1928; 370 O. G. 757)

The invention described herein may be manufactured and used by or for the Government for governmental purposes, without the payment to me of any royalty thereon.

This invention relates to the art of radio signaling and particularly to improvements in receiving systems of radio signals. One object of this invention is to provide methods and means for the selective reception of radio signals; another object is to provide a method for the elimination of interfering signals of definite frequencies.

In my copending application, Serial Number 294,742, filed July 23, 1928, I have described a method for the elimination of interferences in the reception of radio signals based on the use of a wave conductor in combination with a receiving circuit system. It is shown there that by connecting a wave conductor to the antenna, and suitably adjusting the wave conductor in relation to the frequency of an interfering signal, that particular interfering signals may be completely eliminated by the wave conductor rendering the receiving system proper free to receive signals of other frequencies differing from the frequency of the particular interfering signal. Actual experience shows that in such an arrangement it is possible to receive signals of frequencies close to the frequency of an interfering signal rendering the interfering signal practically inaudible while not impairing the efficiency of reception of signals of slightly different frequencies. Without the use of the wave conductor arrangement the desired signals would have been completely blanketed by the much stronger interfering signals. To cite a specific case within applicant's experience, a station in Washington, D. C., which when tested was operating on 640 kilocycles came in very loud on the frequency of a New York station which operated on 660 kilocycles. When the Washington station was in operation, applicant found it impossible even with the very

best selective receivers available to hear the New York station without interference. With the wave conductor arrangement, however, the Washington station was rendered inaudible when the receiver was tuned to the frequency of the New York station and the strength of the signals of the said New York station were not impaired in the least. 50

It was pointed out in the pending patent application referred to above that the wave conductor is to be adjusted for a quarter wave length or an odd multiple of quarter wave lengths and the extreme end of the wave conductor to remain open. The adjustment is preferably effected by varying the distance 55 separation of a solenoidal coil from a grounded metal plate which together forms what is called here a wave conductor, that is one on which a wave development is effected.

This invention embodies the same principle in a modified form. I find that equally good results in the matter of interference elimination are obtained by using a wave conductor of approximately double the length, that is a half wave length conductor and grounding the extreme end. The improvements contemplated in this invention will appear evident from the description and discussion of the accompanying drawing which show typical embodiments of this invention. 65 70 75

In the drawing Figure 1 shows an embodiment of the invention in which a single wave conductor is used for the elimination of an interfering signal of a particular frequency;

In Figure 2 a modification is shown in which three separate wave conductors are used for the simultaneous elimination of three interfering signals of different frequencies;

Figure 3 is a detailed drawing showing a mechanical arrangement for effecting an adjustment of a wave conductor in a view in longitudinal section.

Having particular reference to the draw- 80 85 90

ing in which the same numbers designate similar parts;

In Figure 1 the antenna 1 is connected to receiving circuit system 2 which is grounded at 3. At the junction point 4 where the antenna connects to the receiving circuit system, there is also connected a wave conductor which consists of a solenoidal coil 5 and a metal plate 6 in proximity to the coil, the metal plate being grounded at 3. The opposite end of the said coil is also grounded as at 3. The operation of the invention is as follows: The wave conductor 5, 6, 3, is suitably adjusted preferably to a half wave length or a multiple of half wave lengths of the interfering signal, the adjustment is affected by varying the distance separation of the coil 5 from the grounded metal plate 6, thereby varying the distributed capacity of the coil. When the proper adjustment is made a zero potential is established for the interfering signal at the junction point where the antenna connects to the wave conductor and receiving circuit system thereby rendering the receiving system free from any interferences by the signals of that particular frequency. For any other frequency, however, the wave conductor has very little effect, if any, and the receiving system responds in the usual manner. With this arrangement therefore it is possible to completely eliminate the effect of an interfering signal of a particular frequency, without reducing appreciably the efficiency of the receiving system for signals of other frequencies. This is amply borne out by experience and is in accordance with the mathematical deductions that I have worked out.

The embodiment of the invention shown in Figure 2 differs from Figure 1 in that three separate wave conductors 7, 8; 9, 10; 11, 12; are connected at one end to the junction point 4 where the antenna connects with the receiving circuit system. The opposite ends of each of these wave conductors are separately grounded. Each of these wave conductors is separately adjusted to the frequency of a different interfering signal thereby preventing any of three different interfering signals of different frequencies for which these wave conductors are in adjustment to affect the receiving circuit system.

This method may be extended for the elimination of interferences from any number of transmitting stations by the simple expedient of connecting at 4 a number of wave conductors each separately adjusted to a frequency of each of the interfering signals.

Figure 3 is a detailed drawing showing a cross section of a mechanical arrangement for the adjustment of a wave conductor, in which a supporting frame, consisting of uprights 13 and 15 and a base 14, supports a solenoidal coil comprising a core 16 and wire 16' wrapped thereabout. An adjustable

metal plate 17 is hingedly connected to the sidewall 13 by means of a pin 21. As a means of adjusting the plate 17 there is provided a screw bolt 18 rotatably mounted in the base 14. A nut 20 is mounted on the screw threads 70 of the bolt 18 and the nut 20 is connected by means of a fork 22 to the plate 17. Thus a rotation of the bolt 18 by the turning of the knob 19 results in a vertical movement of the plate 17 on its hinge and the consequent variation in the separation distance of the plate from the solenoidal coil, the purpose of which adjustment is apparent in the foregoing description.

I claim:

1. In a system for the reception of radio signals, comprising an antenna, a receiving circuit system connected thereto, and a wave conductor, said wave conductor being adjustable to the frequency of an interfering signal, said wave conductor comprising a solenoidal coil placed in proximity to a grounded metal plate, one end of said wave conductor being connected to the junction point of connection of said antenna to said receiving circuit system, and the other end being grounded, the adjustment of said wave conductor being effected by varying the distance separation of said solenoidal coil from said grounded metal plate.

2. In a system for the reception of radio signals, comprising an antenna, a receiving circuit system connected thereto, a wave conductor having one of its ends connected at the junction point of connection of said antenna to said receiving circuit system, the other end being grounded, said wave conductor being adjustable to a half-wave length of an interfering signal.

3. In a system for the reception of radio signals, comprising an antenna, a receiving circuit system connected thereto, a wave conductor having one end connected at the junction point of connection of said antenna to said receiving circuit system, the other end being grounded, said wave conductor being adjustable to a multiple of half-wave lengths of an interfering signal.

4. In a system for the reception of radio signals, comprising an antenna, a receiving circuit system connected thereto, a plurality of wave conductors each having one end connected at the junction point of connection of said antenna to said receiving circuit system, the other end being grounded, each of said wave conductors being separately adjustable to the frequency of a different interfering signal.

5. In a system for the reception of radio signals, comprising an antenna, a receiving circuit system connected thereto, a plurality of wave conductors each of which has one end connected to the junction point of connection of said antenna to said receiving circuit system, the other end being grounded,

each of said wave conductors being separately adjustable to a half-wave length of an interfering signal.

6. In a system for the reception of radio signals, comprising an antenna, a receiving circuit system connected thereto, a plurality of wave conductors each of which has one end connected at the junction point of connection of said antenna to said receiving circuit system, the other end being grounded, each of said wave conductors being separately adjustable to a multiple of half-wave lengths.

In testimony whereof I affix my signature.
15 LOUIS COHEN.
